UNITED STATES PATENT OFFICE.

EDWARD B. ROBY, OF NORTH TROY, NEW YORK, ASSIGNOR TO S. AND R. FOLDING MACHINE COMPANY, INC., OF GREEN ISLAND, NEW YORK, A CORPORATION OF NEW YORK.

DIE FOR COLLAR-FOLDING MACHINES.

Application filed July 30, 1924. Serial No. 729,191.

Among the principal objects which the present invention has in view are: To fold the corners of the hem folds to form a mitered joint therebetween; to mechanically dispose the surplus material at the junction of the hem edges of a garment prior to folding said edges; and to produce at the junction of hem edges, a smooth and even thickness of material.

10 Drawings.

Figure 1 is a plan view of a corner fragment of a female die for upsetting the edge hems of garments of the character indicated.

15 Figure 2 is a vertical section of a corner thereof, the section being taken as on the lines 2—2 in Figure 1.

20 Figure 3 is a similar view on enlarged scale showing in conjunction therewith a fragment of the garment to be pressed, and a portion of the male die for pressing the same, the latter being shown in the position prior to engaging the garment.

25 Figure 4 is a similar view showing the male die as seated with the corner portion of the garment turned thereunder.

30 Figure 5 is a similar view showing the die holding the corner portion in place and the folders in position to overturn the hem edges of the garment.

35 Figure 6 is a corner fragment of the garment showing in dash and dot lines the lines of folding of the corner portion and hem edges adjacent thereto.

Figure 7 is a perspective view of a fragment of the garment showing the corner portion as laid and the hem edges adjacent thereto in standing position prior to being folded.

40 Figure 8 shows the corner fragment of the garment with the hem edges folded in position.

Description.

The immediate purpose of the present invention is to provide mechanical means to fold the hem edges of collars for men's wear, and particularly the hem edges of collars known as "semi-soft" collars. The blanks or shapes from which the collars are made are cut in accordance with any desired method forming corners in accordance with the design of the garment as shown substantially in Figure 6 of the drawings. These blanks or shapes are placed in dies such as indicated

by the fragment shown in Figure 1 of the drawings.

In subsequent operation of the machine, the material or blanks are first pressed down in the dies, the extreme corners of the surplus material found there is pressed down upon the body of the blank while the marginal edges herein termed the "hem edges," are up-set by the male die passing down between the side walls of the female die to stand the edges as indicated. The purpose of the present invention might be said to stop here for the remainder of the action whereby the upstanding or hem edges are overturned on the male die and there pressed or creased is well known, and is in fact substantially the operation of the machine disclosed in an application for patent for improvements in "machines for folding the edges of textile and similar articles," filed by me the 22nd day of June, 1923, Serial No. 647,094, to which application cross reference is here made. When the operation is complete, the corner of the garment will be found to be disposed as seen in Figure 8 of the drawings. It is well known that after the hem edges are pressed in this manner by machine, the garment is delivered to seamstresses, who then finish the hem stitches in the usual manner.

With the above purpose in view, the die 15 is provided at the side edge thereof with an upstanding block 16. The block 16 has an inner corner 17 from which radiate the overhanging sections 18. The overhanging sections 18 operate upon the garment when placed in the die 15 to curl the corner extension of the garment, indicated in the drawings by the numeral 19, forward. The corner extension 19 of the garment bridges between the overhanging sections 18 and does not enter between the extensions 18 or into the corner 17 thereof. This position is shown best in Figure 3 of the drawings.

As shown in Figure 3 of the drawings, the fabric forming the garment 20 is so disposed that the marginal edges rest on the rails 21, while the portion 19 is upstanding and bridges across and below the gap formed by the extensions 18.

When now the male die is moved toward the die 15, the corner of the forming die 22 enters between the extensions 18 of the corner block 16. The corner portion 19 of the

garment is engaged and is depressed. The corner portion 19 of the garment 20 is thus carried into the die 15 below the forming plate 22 of the male die, while the hem edges 23 are left upstanding, as seen best in Figure 4 of the drawings. The plate 22 being now at rest, the folding members 24 of the edge folding machine are moved over the forming plate 22 toward the center of the die 15, thereby turning down the hem edges 23, as shown in Figure 5 of the drawings.

As explained fully in the application to which cross reference is above made, the pressure necessary to permanently crease the material to retain the hem edges in position is set or pressed by the bed of the die 15, lifting to exert the necessary pressure upon the material to set or crease it permanently.

When the members 24 are retracted, the die and the forming plate 22 thereof, lift the garment out of the die 15 so that the operator can immediately and conveniently extract the garment from the plate 22.

It will now be found that the corner for the shaping and folding of which the present invention is particularly designed, has been folded so that the turned ends of the hem edges meet in mitered arrangement and the material is disposed evenly at both sides of the mitered joint thus formed.

Claims.

35. 1. A mechanism for making a corner fold on a garment, comprising in combination, a female die, means at the corner of said female die for moving the corner portion

of the garment into the path of a forming die, means including a forming die for overturning said corner portion and upturning the hem edges on either side thereof, and means for folding said hem edges over on said overturned corner portion. 40

2. A mechanism for making a corner fold 45 on a garment, comprising in combination, a female die, a male die adapted to cooperate therewith, and a block disposed at the corner of said female die and adapted to hold the corner portion of the garment over the main portion of the female die so that it will be engaged and overturned by said male die. 50

3. The combination as claimed in claim 2 in which said block is provided with overhanging sections radiating from the inner corner thereof. 55

4. A collar folding machine comprising in combination, a female collar shaping die, a block disposed at the corner of said female die and adapted to hold the corner portion of the collar over the main portion of the female die, a male forming plate shaped in accordance with the collar and having a corner adapted to engage and overturn the corner portion of the collar held by said block, said female die having marginal rails adapted to cooperate with the male die to turn the hem edges into an upstanding position when the male die enters the female die and overturns said corner portion of the collar, and means for folding said hem edges over on said overturned corner portion. 60 65 70

EDWARD B. ROBY.
